UNITED STATES PATENT OFFICE.

TIMOTHY R. COURTENAY, OF NEW YORK, N. Y.

DESIGN FOR A PENNANT, BOOK-COVER, OR SIMILAR ARTICLE.

53,487.

Specification for Design.

Patented July 8, 1919.

Application filed January 25, 1918. Serial No. 213,815. Term of patent 7 years.

To all whom it may concern:

Be it known that I, TIMOTHY R. COURTENAY, a citizen of the United States, residing at New York, in the county of Bronx and State of New York, have invented a new, original, and ornamental Design for Pennants, Book-Covers, and Similar Articles, of which the following is a specification, reference being had to the accompanying drawing, forming part thereof.

The figure is a plan view of a pennant illustrating my new design.

I claim:

The ornamental design for a pennant, book cover, or similar article, as shown.

TIMOTHY R. COURTENAY.

Witnesses:

HARRY COURTENAY,
THOMAS COURTENAY.
